UNITED STATES PATENT OFFICE.

CHARLES W. ANDREWS, OF DULUTH, MINNESOTA.

COMPLETE GASIFICATION OF SOLID FUEL.

Application filed April 20, 1921. Serial No. 462,992.

To all whom it may concern:

Be it known that I, CHARLES W. ANDREWS, a citizen of the United States, residing at Duluth, in the county of St. Louis, 5 and State of Minnesota, have invented a new and useful Improvement in Complete Gasification of Solid Fuel, of which the following is a specification.

The principal object of the present invention is to provide for the complete gasification of solid fuel in such a way that the operation is conducted with a degree of rapidity of throughput of coal consonant with the best present day practice and in such 15 a way that the apparatus employed is comparatively compact and inexpensive.

To these and other ends hereinafter set forth, the process, generally stated, consists in passing a fuel column through an externally heated vertical retort or chamber 20 at a rate, established by the best present existing practice, and appropriate for the economical production of coal gas and coal products at the upper part of the column 25 and thus establishing a rate of coke travel or throughput for the lower part of the column, continuously converting substantially all of the coke throughput into water gas by the introduction of steam at the 30 lower part of the column, and co-ordinating the rate of production of water gas with the established rate of coke travel by providing a sufficiently enlarged heat exchange surface in the lower portions of the column. 35 The invention also comprises the apparatus and improvements to be presently described and finally claimed.

In the drawings forming part hereof—
Figure 1 is an elevational view principally 40 in section, and

Fig. 2 is a horizontal section on line 2—2. In the drawing 1 is a vertical retort or chamber externally heated through its walls and proportioned and adapted for the economical production of coal gas according to 45 commercial practice. 2 is a water gas generator communicating with the chamber 1 and externally heated through its wall and it is characterized by the fact that the area 50 of its heat exchange surface or wall 3 is sufficiently enlarged to insure that the temperature of substantially all the coke from the part 1 passing through it can be maintained sufficiently high for the water gas 55 production, thus providing for the manu-

facture of water gas in co-ordination with the manufacture of coal gas and with the rate of feed of coke determined by the requirements of efficient operation of the coal gas retort or chamber 1 and with the temperature at which the steam is introduced into it. The form of the water gas chamber 2 is not of the essence of the invention so long as it has the necessary heat exchange surface. The combustion chamber 4 surrounds the water gas generator 2 and extends from approximately the bottom to the top thereof where it discharges to the recuperator direct or after passing around and heating the part 1, and it is shown as provided with baffle plates 5. Into this chamber 4 there is appropriately introduced air that may have been heated by a recuperator, not shown but well understood, and preferably a portion of the blue gas, in most cases 60 about half of it; however the mixed gas leaving the apparatus and after having been stripped and deprived of ammonia and tar may be used. 6 indicates an example of an air inlet, 7 an example of a gas passage, and 65 8 an example of a connection to the recuperator. It is an important feature of my invention that the enlargement of the heat exchange surface of the part 2 need be materially less in cases where the steam introduced into the part 2 is highly superheated, 70 for example, to substantially 1500° F. and preferably to a temperature above that required for the water gas reaction. 9 is a superheating chamber for the steam and 75 its wall 10 is also the wall of the combustion chamber 4, and the relative location of the superheater and generator in the brickwork setting makes it practical to transfer such highly superheated steam, as 80 by connection 11, without heat loss, but the steam may be highly heated by any suitable means.

In the practice of the invention by means 85 of the described apparatus, solid fuel is fed downward through the externally heated vertical retort or chamber 1 at a normal rate, that is to say, at a rate appropriate for making coal gas according to good commercial practice. From the part 1 the hot coke 90 reaches the part 2, and is there fully utilized for the continuous manufacture of water gas, because the enlarged heat exchange 95 surface and the temperature of the steam are such that this can be done in co-ordinat- 100 105 110

tion with the rate of travel of the coke which is fixed and established by the coal gas making operation conducted in the part 1.

5 At the base of the retort the residue substantially free from carbon is delivered. With certain kinds of coal the ash may so adhere to the coke that even with my invention the ash coating will prevent the complete gasification of all the coke in the water gas generator and in that case the coke can be reclaimed and utilized.

It will thus be seen that by this process coal is carbonized at a rate of throughput 15 per unit of average cross section of the retort 1 which is not less than that existing in the present best practice. To convert the resulting throughput of coke into blue gas requires the application of so many heat 20 units—for example, it requires about three times as much heat in part 2 as is required in part 1—that heretofore the first step of the process was slowed down or the coke was removed and utilized elsewhere, but by 25 my invention this great number of heat units is successfully supplied in the part 2 without slowing down the first step or removing coke from the apparatus. It may be remarked that in some cases the blue gas 30 leaving 2 at 7 may be, in whole or in part, carburetted and not burned in the chamber 4, and in that case it is replaced by other fuel suitable for the chamber 4.

It will be obvious to those skilled in the 35 art to which the invention relates that modifications may be made in details of procedure and construction without departing from the spirit of the invention which is not limited as to those matters or otherwise than as the prior art and appended claims may require.

I claim:

1. The process of completely gasifying 40 solid fuel which consists in establishing and externally heating a fuel column, permitting the column to descend at a rate substantially as described and appropriate for the economical production of coal gas at the upper part of the column thus establishing a rate of coke travel from the upper part of the column, converting substantially all the coke into water gas by the continuous introduction of steam at the lower part of the column, and co-ordinating the rate of production of water gas with the established rate of coke travel by providing a sufficiently enlarged heat exchange surface at the lower portion of the column.

2. The process of completely gasifying 45 solid fuel which consists in establishing and externally heating a fuel column, permitting the column to descend at a rate substantially as described and appropriate for the economical production of coal gas at the upper part of the column thus establishing a rate of coke travel from the upper part of the column, making water gas by the continuous introduction at the lower part of the column of steam superheated to substantially the temperature of water gas reaction, co-ordinating the rate of production of water gas with the established rate of coke travel by providing a sufficiently enlarged heat exchange surface at the lower portion of the column, and heating the column and steam by the combustion of a portion of the gas generated.

lising a rate of coke travel from the upper part of the column, converting substantially all the coke into water gas by the continuous introduction at the lower part of the column of steam superheated to substantially the temperature of water gas reaction, and co-ordinating the rate of production of water gas with the established rate of coke travel by providing a sufficiently enlarged heat exchange surface at the lower portion of the column.

3. The process of completely gasifying solid fuel which consists in establishing and externally heating a fuel column, permitting the column to descend at a rate substantially as described and appropriate for the economical production of coal gas at the upper part of the column thus establishing a rate of coke travel from the upper part of the column, converting substantially all the coke into water gas by the continuous introduction at the lower part of the column of steam superheated above 1500° F., and co-ordinating the rate of production of water gas with the established rate of coke travel by providing a sufficiently enlarged heat exchange surface at the lower portion of the column.

4. The process of completely gasifying solid fuel which consists in establishing and externally heating a fuel column, permitting the column to descend at a rate substantially as described and appropriate for the economical production of coal gas at the upper part of the column thus establishing a rate of coke travel from the upper part of the column, converting substantially all the coke into water gas by the continuous introduction of steam at the lower part of the column, co-ordinating the rate of production of water gas with the established rate of coke travel by providing a sufficiently enlarged heat exchange surface at the lower portion of the column.

5. The process of completely gasifying solid fuel which consists in establishing and externally heating a fuel column, permitting the column to descend at a rate substantially as described and appropriate for the economical production of coal gas at the upper part of the column thus establishing a rate of coke travel from the upper part of the column, making water gas by the continuous introduction at the lower part of the column of steam superheated to substantially the temperature of water gas reaction, co-ordinating the rate of production of water gas with the established rate of coke travel by providing a sufficiently enlarged heat exchange surface at the lower portion of the column, and heating the column and steam by the combustion of a portion of the gas generated.

6. Apparatus for the complete gasification of solid fuel comprising the combination of an externally heated vertical coal gas retort or chamber, an externally heated water gas generator upon which the coal gas retort or chamber is mounted and with which it communicates, a combustion chamber, means for continuously introducing steam into said water gas generator, a heat exchange wall area for the water gas generator enlarged and coordinated with the coke delivery capacity of the coal gas retort or chamber to heat substantially all of the coke substantially above the temperature of water gas reaction, and a steam superheating chamber the wall of which is common to the combustion chamber.
7. The combination of a brickwork setting, of a steam superheater provided therein, a combustion chamber one wall of which constitutes a side of the steam superheater, a gas making chamber arranged in the combustion chamber, and a connection through the brick work from the steam superheater to the gas making chamber, whereby highly heated steam can be employed.

CHARLES W. ANDREWS.
